LOOP AERIAL

Filed Dec. 24, 1925

Inventor:
Albert G. Harms,

By Fisher, Tolle, Clapp & Sane, Jtly's

UNITED STATES PATENT OFFICE

ALBERT G. HARMS, OF CHICAGO, ILLINOIS

LOOP AERIAL

Application filed December 24, 1925. Serial No. 77,563.

This invention relates to a loop aerial or antenna for collecting radio or electric waves or energy, as for a radio broadcast receiver.

Among the objects of the invention are to provide a novel winding and construction of inside or loop aerial in the form of a complete enclosure or closed loop, the winding or coils of which are of continuous form with no large gaps throughout the surrounding 10 sides, area, or field, or which may be stated as having an area about which the wires are wound to wholly enclose said area, which is smaller and more compact, as well as easier to manipulate than loop aerials heretofore produced, and which has greater inductance 15 than other loops of the same size and better directional effect.

It is also an object of the invention to provide a novel form of loop aerial which includes a frame of novel construction enclosed 20 by a winding on all sides, the frame being such that the winding of the aerial is simplified and quantity production is facilitated.

Other objects and advantages will be apparent as the description proceeds.

In the accompanying drawings:—

Fig. 1 is a top plan view of my novel loop aerial.

Fig. 2 is a side elevation of the device.

30 Figs. 3 and 4 are transverse, horizontal, sectional views taken on the section lines 3—3 and 4—4 of Fig. 2 and looking in the directions indicated by the arrows.

Figs. 5, 6, 7, and 8 are plan views of 35 modifications showing different geometrical shapes.

Fig. 9 is a fragmentary detail elevation showing wire-mounting means for the coil.

Fig. 10 is a similar view of another mounting means, and

Fig. 11 is a detail transverse, sectional view taken on the section line 11—11 of Fig. 10.

Referring to the drawings in detail, and especially to Figs. 1 to 4 inclusive, my novel 45 aerial is shown as comprising a frame including a base 12 having a soft covering 13 of cloth, felt, or rubber, on the bottom to prevent noise and marring or scratching the surface of a table, console, or other cabinet or support upon which the device is usually re-

posed when in use and to keep the base stationary.

Extending up from the center of the base 12 is a pivot pin or post 14, around which and mounted upon the base so as to be rigid therewith, may be disposed a raised circular contact or bearing plate or disk 15 preferably of Bakelite or other insulation having a central aperture receiving the post and a polished contact surface on which rests and turns a similar centrally apertured upper plate or disk 16. The disk 16 is in turn rigidly secured to the bottom wire support or plate member 17 of the frame of the aerial as indicated by the screws 18, said member 17 being preferably of Bakelite or the like.

The frame also includes an upper wire support or plate member 19 mounted on the upper ends of upright corner rods 20 which are rigidly connected to the top and bottom plates or frame members 17 and 19 in any suitable manner as by means of screws 21 passing through the plates and into the ends of the rods 20, thus rigidly mounting said parts in parallel relation.

The winding or wire of the loop is designated at 22 and, as noted, is in the form of a substantially closed loop or field, that is, with the wires arranged to extend in spaced relationship, or wound, wholly about the peripheries of the top and bottom plates and throughout the sides or area of the same and embodies a series of coils. One end of the wire is indicated at 23, at which point it is anchored to one of the plates or end members of the frame, preferably the bottom member 17, and extended through a corner opening, slot, or other wire-receiving, or guiding and retaining means of a spaced series 24 extending entirely around the edges of the plates 17 and 19, as indicated in the drawings and particularly in Figs. 1, 3, and 4.

The wire is then extended lengthwise of the frame to the upper member 19 through the corner opening or wire-guiding means 95 thereof, then diagonally across to the first opening on the adjacent side, then down through the corresponding opening in the bottom member 17, after which the operation of winding is repeated, the coils extending 100

diagonally and increasing in length and width as they approach diagonally opposite corners of the frame and then gradually decreasing in length and width to the opposite corner or winding from the corner where the winding is started. The opposite end of the coil or winding is designated 25 and is preferably anchored beneath the bottom plate 17 at the corner diagonally opposite the corner where the end 23 is located, these ends being adapted for connection with the receiving set and ground in the usual way.

An intermediate lead 26 is connected to one of the coils or loops of the winding 22, intermediate thereof when it is not desired to employ the entire winding of the aerial and less inductance is required. It also will be noted from Figs. 2 and 3 of the drawings that the central loops of the winding at the bottom are preferably extended between the plate or frame member 17 and the disk 16 to prevent interference with the bearing surfaces. It is also preferable to provide an upright or bridge piece 27 on the upper frame member or plate 19 extending from diagonally opposite corners transversely or substantially at right angles to the extent of the coils or loops of the winding 22, so that the latter will cross or intersect this bridge piece at right angles. The bridge piece is preferably of triangular shape and is suitably secured in position vertically on the plate 19 with its apex at the center and has wire guides 28 in the form of openings, grooves, or slots, for the purpose of receiving the wires therein as they are extended or bridged from one side of the frame to the other in the form of a pyramid at the top of the frame, thus giving greater length of coil with greater inductance without materially increasing the size, as well as adding to the attractiveness and appearance of the aerial.

It is to be understood that the guide means 24 may be simple openings, slots, grooves, or other means, for receiving the winding. In Fig. 9 one of the frame members is shown provided with openings 29 having communicating slots 30 preferably inclined to the edge of the frame member and providing an entrance opening into which the wire may be readily passed without the necessity of threading the entire length of the wire through holes and thus facilitating production. The slots arranged as shown, facilitate the entrance of the wires into the openings or guiding means and displacement of the wire is prevented, which is especially due to the inclined entrance portions resisting upward pull or any tendency to displace the wire outwardly at right angles to the adjacent edge of the frame member and by reason of the overhanging portions 31.

In Figs. 10 and 11 of the drawings, a different guiding means is shown in which the frame member is provided with notches 32

preferably V-shaped, and the edge is grooved centrally and longitudinally as indicated at 33 so that when the wires are inserted into the notches 32, they are held by a retaining strip 34 frictionally or otherwise held in the groove over the wires. This not only permits convenient winding to facilitate manufacture of the device but provides a positive means for preventing displacement or withdrawal of the wires from the guiding and retaining means.

As a means of indicating the direction in which the loop is pointed in view of its directional action as a broadcast receiver, suitable means are provided, such as by engraving the lower Bakelite wire support 17, or providing the same with a compass as indicated at 35. In the event that the directions are indicated on the part 17, an arrow or pin 36 is inserted in or mounted on the pivot pin or post 14 to co-operate with the direction marks to show the direction in which the loop is pointed or the compass may be mounted on the pin as shown at 36 in Fig. 2 of the drawings, and the arrow or pointer 37 co-operates with the dial or direction marks 38, the pointer or needle 37 being of the usual magnetic type when employed in connection with the compass. Obviously I do not desire to be limited to any particular construction of direction indicator, and it is also obvious that the same may be arranged otherwise than on the base, whether in the form of a compass or not.

In Figs. 5, 6, 7, and 8 of the drawings, modifications are shown in plan. The frame 39 in Fig. 5 is shown circular with the bridge piece 40 extending diametrically, and the winding 41 with the coils thereof disposed as chords of an arc with the exception of the end coils which are not arranged parallel to the others at the top and bottom but are arranged substantially as shown in Fig. 1. In Fig. 6 the frame 42 is of elliptical or oval shape in plan with the bridge piece 43 and the winding 44 arranged in the same relation as in Figs. 1 and 5. In Fig. 7 the frame 45 is of poly-sided form and is shown hexagonal in plan with a bridge piece 46 extending substantially diametrically between two angular portions or across between two opposite corners and the winding 47 is disposed at right angles thereto. In Fig. 8 the frame 48 is of triangular form in plan, in which the bridge piece is designated at 49 or may be omitted entirely, while the winding is designated at 50. In any of these arrangements, the loops are close together and, irrespective of the geometrical shape, the aerial will accommodate a greater length of wire than has been possible with other types of aerials, especially those having open sides or fields. For this reason, greater inductance is possible than with other loops of the same size, owing to its being enclosed by a winding on all sides.

While I have shown and described my invention in a preferred form, I am aware that various modifications and changes may be made therein without departing from the principles of the invention, the scope of which is to be determined from the appended claims.

I claim as my invention:

1. A loop aerial comprising a frame including top and bottom members spaced apart a distance greater than any dimension of the members, means connecting said members to each other, a bridge piece on one of said members, and wires coiled around the frame and bridge piece in engagement with the members and bridge piece, said wires wholly enclosing the area of the frame and having leads extending therefrom.
2. A loop aerial comprising a frame having top and bottom members spaced apart a distance which is a multiple of any dimension of either of said members, connections between said plates forming uprights bracing the same, a bridge piece on the top member, and wires coiled around the frame diagonally to progressively increase and decrease in size from a central point and detachably engaging the edges of the members and the bridge piece, the wires being arranged to extend in equally spaced relationship to wholly cover the area of the frame.
3. A loop aerial comprising a base having a pivot post, a frame comprising connected top and bottom members mounted to turn on the post, a bridge piece on the top member, said members and bridge piece having slots, a winding comprising a continuous wire removably mounted in said slots and forming coils progressively increasing in size from one side of the frame to an intermediate point and progressively decreasing in size from said intermediate point to the other side to form a substantially closed loop and field.
4. A loop aerial comprising a rotatable frame including top and bottom plates spaced apart a distance greater than any dimension of the plates, means connecting said plates to each other, a bridge piece on one of said plates, and wires coiled about the frame and bridge piece angularly with respect to the edges of the plates and in engagement with the plates and bridge piece, said wires wholly enclosing the area of the frame and having leads extending therefrom.

ALBERT G. HARMS.
